UNITED STATES PATENT OFFICE.

PHILIP J. RIVERS, OF NEW ROCHELLE, NEW YORK.

SAFETY-ELEVATOR.

1,038,961

Specification of Letters Patent. Patented Sept. 17, 1912.

Application filed February 5, 1912. Serial No. 675,632.

To all whom it may concern:

Be it known that I, PHILIP J. RIVERS, a citizen of the United States, and a resident of New Rochelle, county of Westchester, and 5 State of New York, have invented certain new and useful Improvements in Safety-Elevators, of which the following is a full, clear, and exact description.

This invention relates more particularly 10 to automatic means for preventing an elevator car from dropping in case the supporting cable should break.

One of the principal objects of the invention is to provide simple and efficient 15 means which may be located on either or both sides of the car and so arranged that in case the cable should break or other defect arise whereby the car is likely to drop suddenly, the said means will immediately 20 be placed in action and effectually stop the car in its downward movement before the latter has acquired any speed, thereby avoiding all liability of injury to the passenger or passengers within the car.

25 Other objects of the invention are to provide a simple and efficient attachment which may be applied to elevators as ordinarily constructed with substantially no change whatever in the construction, and to provide 30 means which may be located on one or more sides of the car and controlled in its action by the supporting cable to adapt the mechanism to immediately be placed in action should a slack in the cable occur or the 35 said cable break or part for any reason whatever.

Another object of the invention is to provide means which is simple and inexpensive to manufacture, which is effective in use, and 40 which is readily accessible for repairs or for assembling.

A further object of the invention is to provide simple and efficient means whereby one or more cables or elements may be arranged 45 in parallel relation to the elevator guide rails, and which cables are adapted to be gripped by mechanism mounted on the car only when slack occurs in the cable or the cable breaks.

50 With these and other objects in view, the invention will be hereinafter more particularly described with reference to the accompanying drawings, which form a part of this specification, and will then be pointed out 55 in the claims at the end of the description.

In the drawings, Figure 1 is a front ele-

vation showing an elevator with one form of my invention applied thereto. Fig. 2 is a side elevation of the car, showing the invention applied thereto. Fig. 3 is a plan view. Fig. 4 is an enlarged front elevation, partly in section, only a small part of the car being shown. Fig. 5 is a vertical section taken on the line V—V of Fig. 4. Fig. 6 is a sectional plan view through the casing taken on the line VI—VI of Fig. 5; and Fig. 7 is a detail perspective view of one of the brackets.

The car or cage 10 may be provided with guides 11 along its vertical sides which are 70 adapted to span or engage the rails 12, and supporting the car are one or more cables 13 by which the car may be raised or lowered along the rails 12 in the usual way. A plurality of short brackets or guides 14 75 are secured to two of the sides of the car adjacent to the guides 11, and adapted to move vertically between each pair of brackets 14 is a casing 15. This casing 15 is substantially box-like in form and may be 80 closed by a detachable cover 16 so as to adapt the inner part of the casing to be accessible. Passing through the casing is a stationary cable or element 17 which is securely held at its ends and extends the entire distance the car is adapted to travel and is of sufficient strength to bear the weight of the car in case the supporting cable or cables 13 should break or part. As shown 85 there are two cables 17 and two casings 15 90 and mechanisms coöperating with the cables which are located on two of the opposite sides of the car adjacent to the rails 12, but it will be understood that this mechanism as well as the cables or similar means may 95 be variously located and only one mechanism and cable or like means employed. As the two mechanisms are similarly constructed, a description of one will answer for the other.

The casing 15 is open at the lower portion thereof for a part of its length and is provided with an opening at the upper portion thereof through which the cable 17 or gripping device extends to adapt the casing 105 to move freely along said cable during the normal working of the car, and supported within the casing are two gripping elements or devices 18 and 19. These devices 18 and 19 are opposed to each other and are of 110 disk-like form. The devices 18 and 19 are eccentrically pivoted to pins 20 which are

carried by a bracket 21. This bracket 21 may be secured to the casing or may be independent thereof, and said bracket has a backing or part 22 with overhanging hook-shaped portions 23 forming means to properly support the pins or studs 20, the latter being connected on one side by a link or tie element 24 serving as a means to strengthen the hook-shaped portions 23 and hold the studs 20 in their proper position. The eccentric disks or devices 18 and 19 each have a gripping portion 25 which is substantially S-shaped in form, and at the gripping portion the said part is larger than the body 15 of the devices 18 and 19 to partly span the cable 17. These devices 18 and 19 are normally held in a position to permit free movement of the car without said devices engaging the cable 17, but when released, as will be 20 hereinafter described, the said gripping surfaces 25 will be forced against the cable from opposite sides. This will force a part of the cable toward one of the devices and another part toward the opposite device to form a 25 kink or irregular part in the cable when the devices grip the same, and owing to the eccentric action of the devices when caused to grip the cable, any downward movement of the car will only tend to increase the 30 gripping effect, though as an additional means to assist in gripping the cable 17 or other element, the parts 25 may be provided with teeth or serrations to better engage said cable.

35 A pair of links 26 are pivoted at 27 at one end to the gripping device 19 and on opposite sides thereof, and at their opposite ends are pivoted at 28 to a projecting portion or lug 29 of a bracket 30. The 40 bracket 30 is securely held to the bottom or base 31 of the car and has a part or lug portion 32 similar to the part 29 extending upwardly therefrom to which is pivoted, at 33, a pair of links 34. The links 34 are 45 similar to the links 26 and extend on opposite sides of the eccentric disk or device 18 and are pivoted thereto at 35. The links 26 and 34 extend vertically and are angularly arranged with respect to each other and 50 have their pivots 27 and 35 located at a distance from the pivots of the eccentric devices 18 and 19, the said devices each being normally forced to engaging position by a spring 36, one end of which is attached to 55 a lug 37 on the disk or gripping device, and the other end to a lug 38 on the casing 15.

It will be evident that when the casing 15 is forced downward along its guides or brackets 14, the links 26 and 34 will force 60 the gripping surfaces 25 of the gripping disks or devices 18 away from the cable, thus permitting the car and the casing to move freely along the cable or element 17, but as soon as the casing is released, the 65 springs 36 will immediately force the de-

vices 18 and 19 into engagement with the cable 17, thus locking the casing and cable together, and owing to the connection through the bracket 29, the car will be immediately stopped and prevented from further movement until the devices are again released. The casing 15 as well as the gripping devices 18 and 19 are supported by the links 26 and 34 which are so positioned that when the casing is forced downward, the 70 springs 36 will be extended in order that when the casing is released, the said springs will quickly force the gripping devices 18 and 19 on their pivots 20 to cause the surfaces 25 to engage the cable 17. 75 To normally hold the gripping devices 18 and 19 disengaged from the cable 17, various means may be employed. As shown, a lever 39 is pivoted at 40 on opposite sides of the car adjacent to its coöperating casing 15 and free of the movement of the cable or element 17. Each lever 39 has an end 41 which is adapted to bear upon a plate or part 42 of the car and has its other end 43 connected to a cable or flexible connection 44. The connection 44 is secured at its opposite end under tension to a clip or brace 45 and in such a way that the lever 39 is normally moved on its pivot to force the casing 15 downward as shown in Fig. 95 2. This forcing of the casing downward will cause the links to move the devices 18 and 19 on their pivots to release the engaging surfaces 25 from engagement with the cable 17 and in case 100 the cables 13 should break or part, or slack occur for any reason whatever to remove all tension on the connection 44, the springs 36 will immediately force or restore the devices 18 and 19 to their gripping position, which, 105 owing to their connection with the links 26 and 34, will force the entire casing outward at the same time the devices will grip the cable 17 as shown in Fig. 4.

From the foregoing, it will be seen that 110 simple and efficient means is provided whereby an elevator car may be automatically and immediately stopped in case the same should drop by reason of the parting of the cable or other cause; that said means is simple in 115 construction and may be applied to elevators as ordinarily constructed; that said means may be readily made and assembled and is not expensive to manufacture; that said means is so constructed and arranged that 120 the greater the tendency of the elevator car to drop and the greater the weight applied thereto, the greater will be the gripping effect of the safety means; and that said means is automatic in its action.

Having thus described my invention, I claim as new and desire to secure by Letters Patent:—

1. The combination of a support, a bracket carried by said support, a stationary element 130

- adapted to be gripped, eccentrically held and opposed gripping devices having substantially S-shaped gripping surfaces and opposed to each other, links connecting the gripping devices to the support, springs for forcing the gripping devices into gripping position, and means for forcing the gripping devices in the opposite direction to disengage the same from the gripped element.
2. The combination of a support, a stationary element adapted to be gripped, gripping devices opposed to each other and having substantially S-shaped gripping surfaces, means connecting the gripping devices to the support, means for forcing the gripping devices into gripping position, and means for forcing the gripping devices in the opposite direction to disengage the same from said stationary element.
3. The combination of a stationary element adapted to be gripped, eccentrically arranged and pivotally held and opposed gripping devices having substantially S-shaped gripping surfaces, springs for forcing the gripping devices into gripping position, and means for forcing the gripping devices in the opposite direction.
4. The combination of a casing, a bracket

freely movable in said casing, studs extending transversely of said bracket and supported thereby, two disk-like devices pivotally held to said studs and having opposed gripping means, means adapted to be engaged by said gripping means, a movable support, links connecting the gripping means to the movable support, and means for moving the casing relatively to the movable support to force the gripping means to a disengaged position.

5. The combination of a casing, a bracket free to move in said casing, two disk-like devices pivotally held in said bracket and having opposed gripping means, means adapted to be engaged by said gripping means, a movable support, means connecting the gripping devices to the movable support, and means for moving the casing relatively to the movable support to force the gripping devices to a disengaged position.

This specification signed and witnessed this second day of February, A. D. 1912.

PHILIP J. RIVERS.
